UNITED STATES PATENT OFFICE.

EMERY E. BUNCE, OF SUPERIOR, MONTANA.

DESIGN FOR A SAW-SET.

SPECIFICATION forming part of Design No. 32,791, dated June 5, 1900.

Application filed April 26, 1900. Serial No. 14,507. Term of patent 14 years.

To all whom it may concern:

Be it known that I, EMERY E. BUNCE, a citizen of the United States, residing at Superior, in the county of Missoula and State of Montana, have invented and produced a certain new and original Design for Saw-Sets; and I do declare the following to be a full, clear, and exact description of the invention, such as will enable others skilled in the art to 10 which it appertains to make and use the same. The invention relates to a new and original design for saw-sets; and it consists of a design of the shape and configuration shown in the accompanying drawings, of which—

15 Figure 1 is a side view of the invention. Fig. 2 is a front view. Fig. 3 is a rear view, and Fig. 4 is a view of the lower end of the saw-set.

The leading feature of the design comprises the body portion 1, curved at its lower end, 20 as shown at 2, and provided with a head 3, the base of which inclines upwardly at 4 and is provided with a face 5 at an obtuse angle to the beveled portion 4 and with a beveled face 6 at an obtuse angle to the face 5 and 25 thence terminates in the shoulder 7.

What I claim is—

The design for a saw-set, as herein shown and described.

In testimony whereof I have hereunto set 30 my hand in presence of two subscribing witnesses.

EMERY E. BUNCE.
